THIGH GUARD

Alan L. Becket, East Orange, N. J., and Milton B. Reach, Springfield, Mass.; said Reach assignor to A. G. Spalding & Bros., New York, N. Y., a corporation of New Jersey

Application May 3, 1934, Serial No. 723,688

9 Claims. (Cl. 2—2)

The present invention relates to guards for use in games and sports and is embodied, more specifically, in an improved protective guard which serves as an effective protection to the wearer and yet conforms to the other requirements made in connection with devices of this character.

The construction of guards for portions of the body and for use in games such as football, etc., has developed along many lines wherein various substances have been utilized. In the existing forms of guards, the exposing thereof to moisture causes them to become heavy and otherwise to render them unsuitable for use. Accordingly, it is an object of the present invention to provide a waterproof guard which is readily manufactured.

A further object of the invention is to provide a guard which is sufficiently rigid to constitute an effective protection against injury and, at the same time, provide sufficient cushioning therein to provide a structure which answers the requirements of use.

A further object of the invention is to provide a guard of the above character formed of molded elements in combination with a cushioning element and a waterproof covering therefor.

Further objects, not specifically enumerated above, will be apparent as the invention is described in greater detail in connection with the accompanying drawings, wherein:

Figure 1 is a plan view of a guard constructed in accordance with the present invention.

Figure 2 is a view in section, taken on the broken line 2—2 of Figure 1, and looking in the direction of the arrows.

Figure 3 is a plan view showing a slightly modified form of guard.

Figure 4 is a partial sectional view taken on line 4—4 of Figure 3, and looking in the direction of the arrows.

Figure 5 is a view partly broken away, showing molded elements of the guard constructed in accordance with the present invention.

Figure 6 is a plan view showing the cushioning and waterproof outer covering of one side of a guard constructed in accordance with the present invention.

Figure 7 is a view in section, taken on line 7—7 of Figure 5, and looking in the direction of the arrows.

Figure 8 is a view in section, showing a portion of the guard constructed in accordance with the present invention, the left hand portion of Figure 8 illustrating the molded portion of the guard and the right hand portion illustrating the cushioning portion of the guard.

With reference to Figures 1 and 2, a guard is shown as being formed of inner and outer layers 10 and 11, respectively, which may be

formed of a suitable waterproof fabric having the strength and other properties required for service of this character. The inner layer is secured to a plurality of molded layers of reinforcing material as described hereinafter while the outer layer is secured, as by gluing, to a felt or other cushioning substance 12. Suitable straps 13 may be included within the layers above described or otherwise suitably secured to the structure in order that the guard may be secured in a desired position. In the form shown in Figures 3 and 4, the straps 13 are dispensed with and apertures 14 provided through which suitable lacing may be received.

The manner in which the above elements are secured together is illustrated in Figures 5, 6, 7, and 8, wherein the structure is shown in process of manufacture, the inner layer assembly being shown in Figures 5, 7, and 8, while the outer layer assembly is shown in Figures 6 and 8.

Referring to the inner layer assembly, the inner layer is secured to a plurality of suitably formed sheets 15 between any two of which the suspension straps 13 may be anchored. A fabric backing 16 is secured to the outer sheet 15, as shown in Figure 7, and an inner sheet 17 is secured on the inner side of the layer 10. The sheets 15 and 17 of the assembly shown in Figure 7 are formed of a textile fabric impregnated with a thermo setting type of phenol formaldehyde condensation product or similar substances, such as bakelite, and, when positioned as illustrated in the drawings, are molded into the form shown in Figure 8. In this form, the guard is formed with the desired curvature to fit the portion of the body upon which it is to be worn.

In the outer layer assembly, shown in Figures 6 and 8, the outer layer 11 has cemented thereto a layer of felt 12 or other suitable padding material and the elements are formed to correspond in shape with the sheets 15 and the inner layer 10.

It will be seen that the inner and outer layers 10 and 11 are formed with peripheral portions 10' and 11', respectively, which are adapted to be cemented together to form a seal about the edges of the guard. After the inner layer assembly has been molded as shown in the left hand portion of Figure 8, a suitable cement or glue is applied between the adjacent surfaces of the inner and outer layer assemblies. This cement is also applied to the peripheries of the layers and the two assemblies are brought together in such fashion that effective adhesion will result between the assemblies and between the adjacent marginal or peripheral portions 10' and 11'.

The resulting guard structure, by reason of the molded sheets impregnated with the thermo setting type of phenol formaldehyde condensation

product, is quite rigid and thus highly effective as a protective member. The layer of felt or other substance gives the necessary cushioning properties to the guard and by completely sealing the structure at the peripheries thereof, the waterproof layers cause the guard to be practically waterproof. In actual tests, present guard structures embodying felt padding with paper fibre foundations absorb more than the weight thereof in moisture when immersed in water for one minute. The structure described herein absorbs less than half an ounce of moisture when immersed in water for fifteen minutes or longer. Moreover, the provision of the padding material in overlapping relationship with the edges of the molded sheets protects the sharp edges of the molded product and thus prevents injury upon impact therewith. The foregoing structure is thus built around molded foundation members of textile fibre impregnated with a thermo setting type of phenol formaldehyde condensation product or similar substances, unimpregnated textile members being molded therewith and the resulting assembly secured to padding material and an outer waterproof layer as described above.

In order that one manner of carrying out the invention may be described in detail, the foregoing specification has set forth, in detail, the use of a phenol formaldehyde condensation product. Obviously, the particular type of thermo-molded substance may be varied, as long as the substance is pressed and formed under heat. Moreover, the invention is not to be limited to a plurality of molded members, inasmuch as one such member may be so formed as to serve the purpose of a plurality.

While the invention has been described with specific reference to the accompanying drawings, it is not to be limited, save as defined in the appended claims.

We claim as our invention:

1. Protective armor for athletic games and the like comprising a plurality of molded members impregnated with a thermo setting substance of the type of phenol formaldehyde condensation product, a protective member secured thereto, and layers of waterproof material enclosing the said members.

2. Protective armor for athletic games and the like comprising a plurality of molded textile fabric members impregnated with a thermo setting substance of the type of phenol formaldehyde condensation product, a protective member secured thereto, and layers of waterproof textile material enclosing the said members.

3. Protective armor for athletic games and the like comprising a plurality of molded textile fabric members impregnated with a thermo setting substance of the type of phenol formaldehyde condensation product, layers of unimpregnated fabric between which the molded members are secured, a layer of protective material secured to one of the last named layers, and an outer layer covering the protective material.

4. Protective armor for athletic games and the like comprising a plurality of molded textile fabric members impregnated with a thermo setting substance of the type of phenol formaldehyde condensation product, inner and intermediate layers of unimpregnated fabric between which the molded members are secured, the inner layer having a peripheral portion extending beyond the mold-

ed members, a layer of protective material secured to the intermediate layer, and an outer layer covering the protective material and having a peripheral portion secured to the peripheral portion of the inner layer.

5. Protective armor for athletic games and the like comprising a plurality of molded textile fabric members impregnated with a thermo setting substance of the type of phenol formaldehyde condensation product, inner and intermediate layers of unimpregnated fabric between which the molded members are secured, the inner layer having a peripheral portion extending beyond the molded members, a layer of protective material secured to the intermediate layer, and an outer layer covering the protective material and having a peripheral portion secured to the peripheral portion of the inner layer, said inner and outer layers being of waterproof material.

6. Protective armor for athletic games and the like comprising a plurality of molded textile fabric members impregnated with a thermo setting substance of the type of phenol formaldehyde condensation product, inner and intermediate layers of unimpregnated fabric between which the molded members are secured, the inner layer having a peripheral portion extending beyond the molded members, a layer of protective material secured to the intermediate layer, and an outer layer covering the protective material and having a peripheral portion secured to the protective material and the peripheral portion of the inner layer, said inner and outer layers being of waterproof material.

7. Protective armor for athletic games and the like, comprising a plurality of molded textile fabric members impregnated with a thermo setting substance of the type of phenol formaldehyde condensation product, inner and intermediate layers of unimpregnated fabric between which the molded members are secured, the inner layer having a peripheral portion extending beyond the molded members, a layer of protective material secured to the intermediate layer, and an outer layer covering the protective material and having a peripheral portion secured to the protective material and the peripheral portion of the inner layer, said inner and outer layer being of waterproof material, and means on the armor to facilitate securing the same in position.

8. Protective armor for athletic games comprising a foundation member, protective material, and an outer layer, said foundation member including a portion molded by being pressed and formed under heat and having an unmolded periphery, the protective material being positioned between the foundation member and the outer layer, the periphery of the outer layer and the unmolded periphery of the foundation member being hermetically sealed.

9. Protective armor for athletic games comprising a foundation member, protective material, and an outer layer, said foundation member including a portion molded by being pressed and formed under heat, the protective material being positioned between the foundation member and the outer layer, and the peripheries of the foundation member and outer layer being hermetically sealed.
